UNITED STATES PATENT OFFICE.

ARTHUR JUNGHANS, OF SCHRAMBERG, WÜRTEMBERG, GERMANY.

REGULATOR FOR TIME-PIECES.

SPECIFICATION forming part of Letters Patent No. 320,562, dated June 23, 1885.

Application filed February 19, 1885. (No model.) Patented in Germany December 11, 1884, No. 31,642; in France December 18, 1884, No. 165,997, and in England January 12, 1885, No. 418.

To all whom it may concern:

Be it known that I, ARTHUR JUNGHANS, of Schramberg, in the Kingdom of Würtemberg, in the Empire of Germany, have invented 5 certain new and useful Improvements in Devices for Regulating the Balance-Springs of Time-Pieces, (for which Letters Patent heretofore have been granted to me by the Government of Germany, dated December 11, 10 1884, No. 31,642; England, dated January 12, 1885, No. 418, and France, dated December 18, 1884, No. 165,997,) of which the following is a specification.

The object of the invention is to produce a 15 simple device for regulating the balance or hair springs of time-pieces, by which said springs may be quickly and easily inserted without injury to the springs, and by which the difference in the running may be regulated 20 within wide limits without elongating or cutting the springs, or without taking the movements out of the case; and the invention consists of certain details of construction, which will be more fully described hereinafter, and 25 finally be pointed out in the claims.

In the accompanying drawings, Figure 1 represents a front view, partly in section, of my improved regulating device for the balance-springs of time-pieces. Fig. 2 is a side 30 view; Fig. 3, a plan; and Figs. 4, 5, and 6 are details of parts of the regulating device.

Similar letters of reference indicate corresponding parts.

In the drawings, A represents one of the 35 supporting-plates of a clock or other time-piece, through which passes a spindle, i, which is guided in a sleeve, i', of the plate A. The front end of the spindle i, which projects through the dial-plate, is made square for applying thereto a key for turning the spindle, and also a crank, k, which turns with the spindle i, as will be described more fully herein- 40 after. On the sleeve i' is mounted a cam-plate, g, the periphery of which corresponds to the spiral windings of the balance-spring, 45 a—that is to say, it has the same pitch as the latter. To a wing or extension, g', of the cam-plate g is pivoted a crank, h, which carries in a socket a split pillar, e, the outer end of 50 which is made of conical shape. The pillar e can be turned on its axis in the socket of the

crank h, and serves to clamp the balance-spring a by means of a ring, f, that slides along the conical end of the pillar e, so as to compress the split ends of the same. Sometimes it is necessary to cut or break off a portion of the spring a, even to the extent of one or more windings, for the purpose of giving the proper degree of tension to the remainder of the spring a. Heretofore a fixed pillar was 55 used for holding the spring, which required the bending of the spring after each cutting-off operation by means of a pair of pliers, so as to make it true and bring it back to the proper diameter for extending to the pillar. 60 By my construction the bending of the spring a and its detrimental effects is entirely avoided, as the pillar e can be turned in its socket and moved nearer to or farther away from the center of the spring a by simply 65 turning the crank h. The position of the spring a in a plane vertical with the axis of the balance-wheel is regulated by shifting the spring backward or forward between the split portion of the pillar e, and securing it then in 70 position by the clamping-ring f. When the position of the spring has been adjusted with reference to the escapement-lever, and the escapement should still be out of beat, the cam-plate g is turned to the right or left, as 75 required, after which the cam-plate g is secured in position by a set-screw, m, that passes through the plate A, as shown in Figs. 2 and 3.

For regulating considerable irregularities 80 in the running of the time-piece a crank, k, and spring d, of peculiar construction, are made use of. The crank k is keyed to the rear end of the spindle i, back of the cam-plate g, and turned by a key applied to the square front end of the spindle. The bent spring d is 85 attached to the crank k, and provided at its outer end with a slot, p, and a finger, q, which latter slides along the circumference of the cam-plate g, and guides thereby the slot p in the same line. The exterior winding of the 90 balance-spring a is passed through the slot p of the spring d. It follows, therefore, that by turning the crank k the slot p regulates the vibrations of the spring a without changing the position of the latter. By this 95 arrangement considerable irregularities in the running of a clock or time-piece, even up to 100

thirty minutes, may be regulated. The cam-plate *g* is provided with two stops, *n* and *o*, which prevent the crank *k* from being turned too far by the spindle *i*.

5 It is obvious that my regulating device for balance-springs can be used in clocks, watches, and other time-pieces by making such alterations which a person skilled in the art can readily execute.

10 Having thus described my invention, I claim as new and desire to secure by Letters Patent—

15 1. The combination, with a spindle, *i*, cam-plate *g*, mounted upon a sleeve of the spindle, a crank, *h*, pivoted to the cam-plate, a split pillar, *e*, having a clamping-ring, *f*, and a balance-spring, *a*, secured to said pillar, *e*, substantially as set forth.

20 2. The combination of a cam-plate, *g*, a spindle, *i*, having a crank, *k*, a bent spring, *d*, having a slot, *p*, and finger *q*, and a balance-

spring, *a*, passing through the slot *p* of the spring *d*, substantially as set forth.

3. The combination of the spindle *i*, cam-plate *g*, the periphery of which corresponds 25 to the exterior winding of the balance-spring, a crank, *h*, pivoted to said cam-plate and carrying a split pillar, *e*, and a balance-spring, *a*, attached to said pillar, substantially as set forth.

4. The combination of the cam-plate *g*, pivoted crank *h*, axially-turning split pillar *e*, having conical ends, a clamping-ring, *f*, for compressing the conical ends of the pillar, and a balance-spring clamped by said split 35 pillar, substantially as set forth.

This specification signed by me this 11th day of December, 1884.

ARTHUR JUNGHANS.
